GLOVE

Gilbert James Pearce, Westbury, England

Application March 31, 1937, Serial No. 134,163
In Great Britain April 2, 1936

1 Claim. (Cl. 2—169)

This invention relates to improvements in gloves and is applicable to gloves made of leather, woven or felt fabric and other materials capable of being made up into tranks.

5 Although glove tranks have generally been made in the form of sheets having a double-hand outline without a thumb, (the thumb being formed of a separate thumbpiece which fits a thumb opening in the trunk) it is also known to 10 employ tranks which have no thumb opening, but are shaped so that there is no side seam in the finished glove, the main seam being located in the palm of the glove. In one form of glove, which employed separate fourchettes and piecettes, the trunk in effect was comprised of three 15 panels, the centre one forming the back of the glove and containing the backs of the four fingers, one side panel containing the fronts of the four-fingers, the "little" finger front and back forming portions adjoining one another and a second side 20 panel adjoining the other edge of the centre panel and shaped to form the thumb only.

In another proposed construction, the glove was made without quirks or fourchettes from a 25 one piece trunk, with the exception of one small piece which constituted the front and sides of the third finger. In this case, the trunk was comprised in effect of a centre panel bounded by side folds which contained the backs of the four 30 fingers, the fronts of the first or index and "little" fingers being formed on opposite sides of one fold line, one side panel containing the portions for forming the first finger front and the thumb, whilst the other side panel, containing the "little" 35 finger front, was shaped also to form the front and sides of the second finger. Instead of the usual piecettes this construction employed slit trunk tongues, which extended into the forks or junctions between the fingers.

40 It has been realized, however, that to obtain adequate freedom of movement the usual separate piecettes, fourchettes, and quirk should be retained and the trunk cut as simply as possible.

45 The present invention accordingly provides a glove which is constructed of a one-piece trunk without a thumb hole and shaped to provide a glove without a side seam and of separate fourchettes and piecettes for between the four 50 fingers and a quirk for above the thumb, the portions of the trunk forming the front and back of the first or index finger being formed adjoining the portion which forms the thumb, so that the trunk is folded on the thumb side thereof 55 along a line which is an extension of the fold

line between the portions forming the front and back portions of the index finger.

In a preferred construction the trunk is formed adjoining one side of the thumb-forming portions thereof with a V-like tongue which enters 5 a V-gap formed by a slit made on the other side of the thumb portion, a seam extending from one side of the tongue, to a piecette between the first and second fingers, one end of a substantially diamond-shaped quirk meeting and being joined 10 to the base of the V-tongue at a point substantially opposite the lower end of the seam which extends to the piecette aforesaid.

The invention is illustrated by the accompanying drawing which shows one embodiment by way 15 of example.

In the drawing, Figure 1 is a plan or face view of the improved trunk; Figure 2 shows the form of quirk, fourchette and piecette employed, and Figure 3 is a pictorial view of the finished glove. 20

The trunk (Figure 1) consists of a central back panel A, having four slit finger pieces, 1a, 2a, 3a and 4a, and two outer panels B and C, the former (B) provided with the complementary finger pieces 1b, 2b, 3b, and the latter (C) with the 25 complementary finger piece 4c and the complementary thumb pieces t¹, t². When the trunk is folded along F¹, F², for seaming the top of the seam commences at S, and extends down as the 30 edges x¹, x², are brought together. The small V or triangular tongue portion y¹, is joined to the gap formed by the opening out of slit y², and the curved edges z¹, z², sewn together to complete the seam Z (see Figure 3). The substantially diamond shape quirk q for the base of the thumb and 35 the form of the fourchettes F, for the sides of the fingers and the piecettes p, for the interstices of the fingers are shown in Figure 2.

If desired, the trunk may be cut so that an 40 opening is formed at the base of the seam in the palm of the glove which can be closed or drawn together after the glove has been put on by means of a press-stud or other fastener.

In a modified form of trunk two short complementary "ledge" portions may be formed on opposite sides of the trunk to give extra width to the glove. The "ledges" extend out from the bottom of the fingerpiece 4c (i. e. from the top of the length marked x²). The quirk q would 45 need to be altered in shape slightly in view of the provision of these ledges. The lower part of the seam edge z² may also be made as a straight continuation of the median portion, instead of offset outwardly as illustrated. 50 55

I claim:—

A glove formed from a one piece trunk laid out to form a central panel and integral side panels adapted to be folded thereover, said central panel 5 provided with four slit finger pieces; one of said side panels having substantially straight and curved contiguous outer edge portions and also provided with three slit finger pieces, and the other side panel having a finger piece for the 10 index finger and complementary thumb pieces, the latter being bounded on the one side by a slit and partially bounded on the other side by a triangular tongue which merges into a curved

edge adapted to mate with the complementary curved edge of the other side panel, piecettes stitched at the bottom of the finger pieces fourchettes stitched to the side of the finger pieces, a substantially diamond shaped quirk for the base of the thumb pieces and a seam connecting the opposite side edges of the side panels and extending up from the mouth of the glove around the tongue and quirk to secure said quirk in place and thence upward to join the piecette 10 between the first and second finger. 5
